J. M. MILLER.
VACUUM PAN, &c.

No. 8,450.

Patented Oct. 21, 1851.

UNITED STATES PATENT OFFICE.

JAMES M. MILLER, OF NEW YORK, N. Y.

IMPROVEMENT IN SUGAR VACUUM-PANS.

Specification forming part of Letters Patent No. 8,450, dated October 21, 1851.

To all whom it may concern:

Be it known that I, JAMES M. MILLER, of New York, in the county of New York and State of New York, have invented certain Improvements in Vacuum-Pans and other Sugar-Manufacturing Apparatus, &c., parts of which are also applicable to other purposes; and I do hereby declare that the following is a full, clear, and exact description of the principle or character which distinguishes them from all other things before known, and of the usual manner of making, modifying, and using the same, reference being had to the accompanying drawings, of which—

Figure 1 is a plan of the heating-pan; Fig. 2, plan of tubes; Fig. 3, cross-section of boiler-pan, &c.; Fig. 4, longitudinal section of apparatus for brown sugar; Fig. 5, a view of the apparatus for manufacturing white sugar; Fig. 1', a section of the condenser; Fig. 2', a plan of the same; and Fig. 3, a section through the boiler, vacuum-pan, condenser, &c.

My improvements consist in the mode of constructing steam-pipes for sugar-pans, and in their arrangement and combination with said pans, and with the boiler that supplies them with steam, by which arrangement the steam is conducted by the shortest possible course through pipes to every part of the pan, and the condenser steam or water has a free and direct course back into the boiler.

I am aware that large pipes have been employed for evaporation in pans, and also that the waste condensed steam has been made to run back through the same pipe into the boiler. Consequently these abstract ideas are not designed to be covered by me in this invention; but in all the attempts of this kind with which I am acquainted a failure has ensued on account of the improper construction of the apparatus, as neither a coil or worm will answer, the distance which the steam has to traverse being too great, and consequently the current through them too strong. This effect I have found in actual practice to be the case, and that the length of tubes or distance from the farthest extremity to the boiler cannot be indefinitely increased without spoiling the effect. There are many other defects, which I will not now enumerate, in inventions of this class hitherto made. I have, after much labor and expense, at last succeeded in constructing an apparatus that will work, and which produces a much greater effect than any other

with which I am acquainted, while the apparatus is much less liable to injury by expansion and contraction of the tubes, which in this may be ever so unequal and ever so rapid without any strain on the parts. The steam is admitted at the center, and none of the pipes are attached to any non-yielding fixture, by which they can be strained. This is of utmost importance in practice. There are two other essential points necessary to be understood before my improvements can be fully appreciated. First, the pipes must be made of as large diameter as is consistent with the maximum thickness of metal to obtain the best circulation, which diameters I have found by careful experiment to be about four inches for the branch tubes and about six inches for the main tube, the metal which I have found best adapted to this purpose being about sixty-pound sheet-copper. The second other important point is so to construct the pipes as to have them as short as possible, and at the same time to cover as much space as convenient in the pan, and it was for this purpose that I adopted the form shown in the drawings in Fig. 2. The pipes for heating and the pipes for the condensing portion of the apparatus are somewhat different in their construction, although their arrangement is not unlike—that is, a series of short pipes branching from a main. The outer ends of the lateral pipes are a little elevated to insure the discharge of any condensed steam within them into the main pipe, which thence finds its way into the boiler, and is reconverted into steam of high temperature, to again convey its heat to the surrounding medium. The center main, *s*, is connected at its center (or if very long in two or more places) with the boiler by short vertical pipes *a*. The boilers are of any ordinary construction, and are furnished with a common safety-valve, *B*. As there is no escape-steam unless the fire is forced so hard as to cause the safety-valve to rise, it is obvious that no supply of water will be required, and to supply this occasional waste very little will suffice. The vertical pipes *a* descend into the top of the boiler, which is located directly under the pans for that purpose. Each of these pipes is fitted with a valve or stop-cock, *c*, for regulating the admission of steam into the tubes *s* in the pan above.

The pans *E* are made in the usual way, and may be made either square, as shown in the

drawings, or round, in which latter case the lateral pipes must necessarily be of different lengths to wholly occupy the greatest amount of space in the pan; and this form is undoubtedly more equable in its operation than the square form, where it can be advantageously employed.

The open pans E, used in the manufacture of brown sugar, are made of any ordinary shape, and placed in a range, all on a level, or nearly so, instead of being one above another, as in the ordinary ranges now in use. These pans are connected at the bottom by openings, which are closed by sliding gates, one of which is shown at *g*, Fig. 3, in dotted lines. It is raised by the lever-handle N. Each of the partitions between the pans after the first is made lower than the preceding one, and the bottoms of all except the first pan are covered with rows of pipes. The first pan has about one-third of its space (next the precipitation) without any pipes in it, which leaves a space for the scum to eddy back into, the course of the scum being backward toward said space from which it is removed.

There is a heating-pan, K, above the series before named, in which I have a series of pipes formed like those in the pans below. These pipes receive the exhaust-steam from the steam-engine, and serve the double purpose of creating a partial vacuum and of heating the cane-juice to a boiling-point directly after it leaves the mill. An inverted-siphon-shaped tube, O, connects with those tubes from below, as shown in Fig. 4, in which there is a common check-valve at P, the case only of which is shown in the drawings. From this the pipe R connects with the air-pump. Besides this, there is another branch on one side, in which is placed a second check-valve, Q, communicating with an escape-pipe, so that if the steam is not all condensed in the tubes or pumped out it may escape through this passage, which is at the same time guarded against the admission of air by the valve Q, which would otherwise be very injurious in operations of this kind. The precipitator L is a little below the heater K, and receives the cane-juice from it in a heated state, when it has time to settle, there being no heat applied in this pan, and as the juice is then discharged into the first pan, E, in the train below through a spout, where the boiling first commences by letting in the steam upon the section of pipes connected therewith. When the second pan is to be charged, the handle N of the gate *g* in the partition between it and the first pan is raised, and the contents are transferred, the first pan receiving a second charge from the heating-pan above. From the second to the third pan the same method is pursued, and so on to the fourth, where the operation is completed. If it is found in practice that one set of pipes do not evaporate fast enough for the purposes required, two or more may be employed, one being placed over another.

It is obvious that the pipes may be used for

various other purposes as well as for sugar-making—such as all other evaporating processes, distilling, &c.; and they may be employed *in vacuo* or otherwise, as is deemed advisable.

For the apparatus for evaporating *in vacuo* for white sugar I employ two (more or less) filters, through which the cane-juice passes from the precipitator that is placed above said filters. The filters are upright cylinders placed somewhat below the vacuum-pans, with which they are combined, so that the vacuum-pan shall perform the office of creating vacuum in the filter and also boil *in vacuo*. These filters receive the cane-juice at their lower ends. The first, O, receives the juice from the precipitator through a long descending pipe, T, regulated by a stop-cock, 1. The lower part of this filter, up to the dotted line X, serves as a precipitator. From this line to W the space is filled with the filtering medium, through which the cane-juice is filtered upward, and descends through a second pipe, in which is a stop-cock, 2, to the bottom of the second filter, O', where it again ascends through the filtering medium from X to W, and thence enters through stop-cocks 3 and 4 to the vacuum-pans through pipes J and V, the juice being drawn up by the vacuum in the pan. The filters are cleaned by admitting steam at the top, and thus forcing the impurities down through the filtering medium. In the vacuum-pans are placed series of pipes, as in the open pans above described, as shown in section, Fig. 1'. On the top of the vacuum-pans are domes, from the top of which are pipes conducting to the condenser D. (Shown also in section in Figs. 1', 2', and 3'.) In the tubular condensers that have generally been used the shell of the condenser necessarily had to sustain the pressure of the atmosphere caused by the vacuum. This on a large surface was very great, requiring the shell to be made very stout and well braced, and all expansions and contractions were necessarily straining all its joints; but in my condenser the whole system works from a center as a base or fixture, allowing all its arms or radii to expand and contract in any manner without injury to their joints. The horizontal pipes extending from the main nearly to the case have within them smaller pipes, that are attached all round to the edge of their outer ends, as clearly shown in the enlarged view at Fig. 1', the outer pipes being open at the end and the inner one having a convex end piece at its inner end. The pipe thus constructed is as if one half of it was turned back within the other and reversed, forming an annular space between the two halves for the steam to enter, the body of the cold water surrounding it on the outside, and also on the inside.

Having thus fully described my improved apparatus and its purposes, I claim as my invention and desire to secure by Letters Patent—

1. The evaporating and condensing tubes

constructed and arranged in the manner and for the purpose set forth, they being attached at one point only, through which the steam enters, having freedom to expand or contract without injury, and the evaporating-tubes being combined at the center of the series, as above specially set forth, with the boiler, the steam is conveyed from the boiler to the extremities of all the tubes in the most direct manner.

2. Connecting the filters with the vacuum-pan in the manner and for the purpose set

forth, so that the vacuum-pan shall perform the double office of making the vacuum in the filter and boiling *in vacuo*.

3. The construction and arrangement of the condenser-tubes above specified, the ends of said tubes being turned back inwardly nearly the whole length of the outer portion, as distinctly shown in the drawings.

J. M. MILLER.
